UNITED STATES PATENT OFFICE.

RAYMOND CALPIN, OF EVERETT, MASSACHUSETTS, ASSIGNOR TO A. S. CAMPBELL COMPANY, OF EAST BOSTON, MASSACHUSETTS, A CORPORATION OF MASSACHUSETTS.

CURTAIN-WINDOW INSTALLATION.

Application filed January 14, 1925. Serial No. 2,287.

This invention aims to provide an improved curtain window installation, improved frame members for the installation, and the method of making a frame element.

5 In the drawings, which illustrate two preferred embodiments of my invention:—

Figure 1 is an elevation view of the installation showing parts broken away to expose the construction of the glass-holding 10 frame member;

Fig. 2 is a full size fragmentary view of one corner of the installation showing a portion of the cover frame broken away;

Fig. 3 is an enlarged section on the line 15 3—3 of Fig. 2;

Fig. 4 is an enlarged section on the line 4—4 of Fig. 2;

Fig. 5 is an enlarged section on the line 5—5 of Fig. 1;

20 Fig. 6 is a series of detail sections showing the various steps in forming the beaded portion on the glass-holding frame member;

Fig. 7 is a section on the line 7—7 of Fig. 5;

25 Fig. 8 is an enlarged section on the line 8—8 of Fig. 2; and

Fig. 9 is a section similar to Fig. 5, but showing the second preferred form of frame-holding means.

30 Referring to the drawings, I have shown a curtain window installation in which the glass may be easily and quickly removed by simply removing a cover frame part while the rest of the frame parts remain secured 35 to the curtain fabric.

In the first form of my invention illustrated in Figs. 1 through 8, I have shown a curtain window installation which comprises a curtain 1, which may be the curtain of an 40 automobile, a glass 2, and a plurality of frame members for securing the glass to the curtain.

The frame members comprise a glass-holding frame member 3 secured to one side of 45 the curtain by a plurality of prongs 4 presented by a prong-presenting member 5 (Fig. 3) and a cover frame member 10 adapted to snap over the glass-holding frame member 3 and hold the glass 2 in place. The 50 prongs 4 pass through the curtain and through slots 6 in the glass-holding frame member and are bent against the surface of said frame to "permanently" secure both frame members 3 and 5 to the curtain.

55 The prong-presenting member presents a

relatively wide fabric-gripping surface at one side thereof and at the other side presents a centrally located beaded portion 7 for strengthening purposes.

The glass-holding frame member 3 is provided, at its inner periphery, with an upstanding wall 8 which surrounds the glass 2 as best illustrated in Figs. 3, 4 and 5. The glass is held in position by the prong-presenting frame member 5 at one side, which 60 extends beyond the wall 8 with the curtain 1 as a cushion, and on the opposite side by the reversely bent flange portion 9 of the cover frame 10, which contacts directly with the glass. The reversely bent portion 9 of the 65 cover frame 10 is held against the glass by a plurality of lips 11, herein shown as two in number, which are struck from the reversely bent portion 9 and engage slots 12 provided in extended portions of the wall 8, 70 as best shown in Figs. 5 and 7. The cover frame is somewhat yieldable laterally because of its formation, and the sides carrying the lips 11 may be pressed manually toward each other to permit the lips to be 75 hooked into the slots 12. When the sides are released, the frame will assume its normal formation and the lips 11 will then enter the slots 12, as shown in Fig. 5. The cover frame is also secured to the glass-holding frame 80 member 3 by snapping the inwardly curved outer periphery thereof over the upstanding outer peripheral beaded portion of the frame member 3, as best illustrated in Figs. 3, 4 and 5.

The above mentioned arrangement of locking the cover frame 10 to the glass-holding frame 3 prevents accidental loosening of the cover frame which would result in the glass falling out of the frame member 3.

In assembling the installation, the frame members 3 and 5 are first secured to the curtain 1, as hereinbefore described. Then the glass is placed in the aperture surrounded by the wall 8 and the cover frame is engaged with the glass-holding frame member 3, first at the inner periphery, as described, and then snapped over the outer periphery. Thus the glass is held firmly in place by the cover frame and may be removed by merely releasing the cover frame without in any way disassembling the remaining frame members.

While the glass-holding frame member 3 may be stamped from a single piece of metal,

as is the usual practice, I prefer to press it from the material which is left over from the centers of the remaining frame members. Thus I make use of otherwise waste metal 5 and reduce the cost of manufacture without affecting the strength or durability of the frame.

The preferred method of forming the glass-holding member comprises providing 10 two end pieces which include the corners of the frame and two side pieces, all of which are secured together to provide a frame member which has a continuous wall 8 and a continuous beaded portion 13.

15 The preferred method of forming the joint and connecting the parts of the frame 3 together is best illustrated in Figs. 1, 2, 3 and 8. The ends 14 of the side strips (Figs. 2 and 8) are bent upwardly so as to over- 20 lap the ends 15 of the end pieces from which are punched, or otherwise formed, rivets or eyelets 16 which pass through apertures in the ends 14 of the side strips. Thus the parts of the frame are secured together.

25 The wall is made continuous, without overlapping, by cutting away a portion of the wall which corresponds in length with the overlapped portions of the ends of the frame parts, so that the wall on one piece abuts the 30 wall of the cooperating piece. The beaded portion 13 is made continuous in substantially the same manner as the wall 8 is made continuous.

35 The beaded portion 13 of the glass-holding frame member is formed by a series of operations, as best illustrated in Fig. 6. First an upstanding flange is formed, then the upper portion of the flange is pressed inwardly to provide an initially bent portion. After the parts of the frame are secured together, in the above mentioned manner, the upstanding initially bent flange portions are bent inwardly to form the bead 13. The advantage of forming the bead after the 40 parts are secured together is to have the beaded portion on each part align with the other beaded portions, thereby providing a continuous edge over which the cover frame 45 10 may be snapped.

50 Referring now to Fig. 9, I have shown a second preferred form of means for securing the cover frame 10 to the upstanding wall 8 of the glass-holding frame member 3. In this instance, the reversely bent portion 9 of the cover frame 10 is spaced away from the rest of the frame so as to provide a groove 55 17 which engages a plurality of lips 18 bent from the upper periphery of the wall 8. Thus the cover frame 10 is interlocked with the frame 3.

50 While I have shown and described preferred embodiments of my invention, it will be understood that changes involving omission, substitution, reversal and alteration of parts and even changes in the mode of oper-

ation, may be made without departing from the scope of my invention, which is best defined in the following claims.

Claims:

1. A curtain window installation comprising, in combination, a glass, the curtain frame elements secured to opposite sides of the curtain, one element supporting the glass at one side and the other element holding the glass against lateral movement and 75 a cover frame element removably secured to the installation to provide the only means for supporting the glass at that side of the curtain at which the cover frame is located, said cover frame element being quickly removable and attachable to permit changing 80 of the glass while the remainder of the installation remains intact.

2. A curtain window installation comprising, in combination, a glass, the curtain fabric, a glass-holding frame secured to the curtain, and a cover frame secured directly to the inner and outer peripheral portions of said glass-holding frame by cooperating means presented by said frames, said cover frame thereby concealing said glass-holding frame and holding said glass in position therein, said cover frame removable independently of the rest of the installation to permit changing the glass without removing the glass-holding frame from the curtain. 90

3. A curtain window installation comprising, in combination, a glass-holding frame member, a flexible fabric, a second frame member, means formed integral with said frame members for permanently securing them to said flexible fabric, a glass held against lateral movement by said glass-holding frame member and a cover frame adapted to engage the inner and outer edges of said glass-holding frame member to secure it in position and to overlie a portion of said glass to provide the only means for holding it in position in said glass-holding frame member. 100

4. A curtain window installation comprising, in combination, a glass-holding frame member, a curtain, a second frame member presenting a plurality of prongs for permanently securing said frame members to opposite faces of said curtain, a glass supported by a portion of the inner edge of said second frame member with the curtain interposed between said glass and said supporting edge, an upstanding wall presented by said glass-holding frame for holding said glass against lateral movement and a cover frame having a reversely bent inner edge to provide the only means for holding said glass in said glass-holding frame overlying said glass adjacent its edge, said cover frame provided with means adapted to engage the outer and inner edges of said glass-holding frame member to secure it thereto. 110 120 125

5. A curtain window installation comprising, in combination, a glass-holding frame member, a curtain, a second frame member presenting a plurality of prongs for permanently securing said frame members to opposite faces of said curtain, a glass supported by a portion of the inner edge of said second frame member with the curtain interposed between said glass and said supporting edge, an upstanding wall presented by said glass-holding frame for holding said glass against lateral movement and a cover frame having a reversely bent inner edge overlying said glass adjacent its edge to provide the only means for holding said glass in said glass-holding frame, said cover frame presenting lips to engage slots in said wall and adapted to snap over the outer periphery of said glass-holding frame member to secure it thereto.

6. A curtain window comprising, in combination, a prong-providing frame member and a prong-receiving member secured to opposite sides of a curtain fabric, one of said frame members presenting at its inner periphery an upstanding wall, and a cover frame member secured at intervals to said upstanding wall and engaging a glass surrounded by said wall, said cover frame providing the only means supporting the glass at one side of the installation and when removed permitting removal of the glass without disturbing the remainder of the installation.

7. A curtain window comprising, in combination, a prong-providing frame member and a prong-receiving member secured to opposite sides of a curtain fabric, one of said frame members presenting at its inner periphery an upstanding wall, and a cover frame member extending beyond said wall to provide a glass-engaging surface, said cover frame secured to said wall at intervals by a plurality of lips extending into slots located in said upstanding wall.

8. A curtain window comprising, in combination, a glass-holding frame member presenting an upstanding peripheral wall at its inner periphery and a beaded portion at its outer periphery, a prong-presenting frame member presenting a plurality of prongs for engagement with the glass-holding frame member for securing said frame members to opposite sides of a curtain, said prong-presenting frame and the curtain extending beyond said upstanding wall to provide a cushioned abutment for a glass and a cover frame member presenting a reversely bent edge portion extending beyond the upstanding wall for holding the glass in place, said cover frame presenting a plurality of lips

for engagement with slots in said upstanding wall to secure the inner periphery of the cover frame to the glass-holding frame and the outer periphery of said cover frame snapped over the beaded portion of said glass-holding frame to secure both frame parts together.

9. A curtain window frame including a glass-holding frame part presenting a beaded portion at the outer periphery thereof and an upstanding wall at the inner periphery thereof, and a laterally distortable cover frame for concealing said glass-holding frame part, said cover frame presenting a plurality of lips engageable with said upstanding wall by distortion of said frame, said lips being held in engagement with said wall by snapping the outer peripheral edge portion, of said cover frame, over the beaded portion of said glass-holding frame part.

10. A curtain window installation comprising, in combination, a curtain fabric, a glass, glass-positioning frame members permanently secured to said curtain fabric for positioning the glass relative thereto and a cover frame member assembly secured to one of said frame members for holding said glass in place, said cover frame member being removable from the frame members secured to the curtain to permit changing the glass while the remainder of the frame members remain secured to the curtain fabric.

11. A curtain window installation including a plurality of frame members secured together to hold a glass in place relative to a curtain fabric, an upstanding wall presented by one of said frame members adjacent the peripheral edge of the glass to prevent lateral movement of the glass, and a cover frame presenting interlocking means for cooperation with means presented by said upstanding wall to secure said cover frame member in position to hold the glass in place at one side of the installation.

12. A curtain window installation including a plurality of frame members secured together to hold a glass in place relative to a curtain fabric, an upstanding wall presented by one of said frame members adjacent the peripheral edge of the glass to prevent lateral movement of the glass, a plurality of slots presented in said wall for reception of lips presented by a laterally yieldable removable cover frame for securing said cover frame member in position to hold the glass in place at one side of the installation.

In testimony whereof, I have signed my name to this specification.

RAYMOND CALPIN.
